(57) **CLAIM**

The ornamental design for a ladder bracket, as shown and described.

DESCRIPTION

FIG. 1 is a perspective view of a ladder bracket showing my new design;

FIG. 2 is a top plan view thereof;

FIG. 3 is a bottom plan view thereof;

FIG. 4 is a front view thereof;

FIG. 5 is a rear view thereof;

FIG. 6 is a right side view thereof;

FIG. 7 is a left side view thereof;

FIG. 8 is another perspective view of the ladder bracket thereof; and,

FIG. 9 is another perspective view of the ladder bracket thereof.

The broken lines are for illustrative purposes only and form no part of the claimed design.
